WEDGE FOR CONCRETE TIE RODS

Daniel C. Hungerford, Chalfont, Pa., assignor to
Star Expansion Belt Company, New York,
N. Y., a corporation of Illinois

Original application July 24, 1935, Serial No.
32,864. Divided and this application September
16, 1937, Serial No. 164,151

5 Claims. (Cl. 25—131)

This invention relates to improvements in
wedges for concrete tie rods.

Its object is to provide a novel wedge which
can be quickly and easily applied to concrete
5 forms and as readily removed when the concrete
is set. It is constructed with impact members
at its ends to facilitate its insertion and removal.
The impact member at the smaller end of the
10 wedge is separated from the wedge by an aper-
ture. It has an extended heel at its larger end
which forms a holding surface when the wedge
is driven in to its extreme position and its other
end is beveled to facilitate its insertion, and
15 may be provided with a wrench socket adapted
to engage the particular type of tie rod with
which this wedge is especially designed to co-
operate.

The body of the wedge is divided by a longi-
tudinal slot with tapered surfaces bordering it.
20 Outside of the tapered surfaces are longitudinal
ribs which merge into the body of the wedge
and into the other end of the structure. The
smaller end of the wedge forms an impact mem-
ber divided by an aperture from the part which
25 closes this end of the slot.

These and other objects of the invention will
be described in the following specification and its
novel features pointed out in appended claims.

Fig. 1 is a front elevation of a wedge which
30 is made according to and embodies the present
invention;

Fig. 2 is a sectional side elevation of the wedge
shown in Fig. 1;

Fig. 3 is a front elevation of the smaller end of
35 a wedge showing a modification of construction,
in this case with its stripping wrench omitted;

Fig. 4 is a front elevation of a wedge of further
modified construction;

Fig. 5 is a sectional side elevation of the wedge
40 shown in Fig. 4; and

Fig. 6 is a sectional side elevation of parts of
a concrete form structure, a tie rod, and of my
novel wedge, illustrating the relative positions
45 of these parts when the wedge is in one of its
extreme positions. Another wedge is shown in
this figure in broken lines to illustrate the manner
of its use as a stripping wrench.

The wedge, designated generally by the refer-
ence numeral 30, comprises a base 31 which is
50 substantially flat to engage a part of a concrete
form structure, such as a waler 50 (Fig. 6), ex-
cept at its lower end where it is beveled, as shown
at 32, to facilitate its insertion between the waler
and one of the heads 11, 12 or 13 of a tie rod 10.
55 The wedge is slotted throughout the greater

part of its length, as at 33, and the sides of the
slot form inclined surfaces 34 supported by lon-
gitudinal ribs 35 at their sides which merge into
the body of the wedge and give it uniform strength
throughout its length. The surfaces 34 slope 5
gradually from the base 31, except at their
lower ends 34A where they are steeper. The
lower end of the slot terminates in a transversely
wider open portion 36 of sufficient size to clear
the rod heads. The upper end of the slot is 10
closed by a portion 37 which forms an anvil
head. Above this head the base is continued
to form a heel 38, the purpose of which will be
pointed out. The lower end of the wedge is ex-
tended, as at 40, and has an aperture 41 which 15
forms a wrench for engagement with the outer
head 13 of the tie rod which is shaped for such
engagement. The end 42 forms an impact mem-
ber which can be used to loosen the wedge. A
cross bar 43 forms a bridge between the apertures. 20

When the parts are assembled as shown in
Fig. 6, the inclined surfaces of the wedge engage
one or another of the tie rod heads 11, 12 or 13,
depending upon the thicknesses of the lumber
used in the form. The heads pass through the 25
opening 36 but ride up first on the steep inclined
surfaces 34A which engage them. This draws
the parts of the mold together and keeps them
from separating. Then the parts may be tight-
ened by hammer blows on the anvil head 37. 30
Fig. 6 shows how the full length of the inclined
surfaces 34 may be utilized. When the wedge
is driven down its full length, its heel portion
38 forms a bearing for it on the waler 50.

After the concrete is set the wedge may be 35
loosened by a hammer blow on its lower end and
then removed. Its wrench end 40 may be used
to twist and break the tie rod. A wedge is indi-
cated at 30 by broken lines in Fig. 6, positioned
for such operation. The wedge itself may be 40
used as a lever to pull out the broken end of the
rod.

In Fig. 3 the lower end of a wedge is shown
with the wrench extension 40 omitted. 45

The wedge shown in Figs. 4 and 5, designated
generally by the reference numeral 30A, differs
from that shown in the preceding figures in the
construction of its ends. The anvil surface 37A
is at the extreme end of the structure and more 50
widely spaced from the part which closes the
upper end of the slot.

The impact member 42A is separated from the
closure for the smaller end of the wedge by a
segmental aperture 41A which, by spacing the 55

part which closes the lower end of the slot, forms a transverse bridge 43A.

This application is a division of application Serial No. 32,864, filed by me July 24, 1935.

5 Structural modifications may be made within the spirit and scope of this invention and I intend no limitations other than those imposed by the appended claims.

What I claim is:

10 1. A wedge having a slot widened at one end to receive, and inclined surfaces to engage a headed form tie and longitudinal ribs bordering said surfaces at the smaller end of the wedge, said ribs being merged into the body of the wedge 15 toward the larger end thereof.

15 2. A wedge having a slot closed at both ends, tapered surfaces bordering the slot and ribs bordering the tapered surfaces, said ribs being merged into the body of the wedge toward the larger end thereof and into the closure at the 20 smaller end of the wedge.

20 3. A wedge having a slot closed at both ends, tapered surfaces bordering the slot and ribs

bordering the tapered surfaces, said ribs being merged into the body of the wedge toward the larger end thereof and into the closure at the smaller end of the wedge, and an aperture 5 through the closure at the smaller end of the wedge.

4. A wedge having a slot widened at one end to receive, and inclined surfaces to engage a headed form tie and longitudinal ribs bordering said surfaces at the smaller end of the wedge, 10 said ribs being merged into the body of the wedge toward the large end thereof and extending at least to the longitudinal centers of the inclined surfaces.

5. A wedge having a slot widened at one end 15 to receive, and inclined surfaces to engage a headed form tie and longitudinal ribs bordering said surfaces at the smaller end of the wedge, said ribs being merged into the body of the wedge toward the large end thereof, the outer surfaces 20 of said ribs being substantially parallel to the back surface of the wedge.

DANIEL C. HUNGERFORD.
